UNITED STATES PATENT OFFICE

JOHN MAYO, OF FAIRMONT, WEST VIRGINIA, ASSIGNOR TO THERMAL ENGINEERING CORPORATION, OF LONG ISLAND CITY, NEW YORK, A CORPORATION OF NEW YORK

LEER

Application filed October 1, 1927. Serial No. 223,449.

This invention pertains to leers for annealing glassware. It covers means for controlling the heat and regulating the temperature throughout the leer.

5 The invention has particular utility in fireless leers of the type disclosed in co-pending application of Orie Shackelford, Ser. No. 187,470, filed April 29, 1927. For convenience of description, therefore, the 10 present invention is illustrated and described as an improvement on the Shackelford leer.

In order that a fireless leer may be adaptable to various sizes of ware it is 15 advantageous to be able to vary the effectiveness of the heat insulation at certain zones in the leer, thereby making it possible to raise or lower the temperature in those zones and thus control the rate of 20 temperature drop through the leer.

In fireless leers the heat is all supplied by the ware itself as it enters the leer fresh from the molding machine, no additional heat being supplied from other sources. 25 Under such circumstances it is evident that heavy ware will radiate more heat than light ware. For instance, bottles weighing twenty ounces each entering the leer at four second intervals will have more excess heat 30 to dispose of than bottles weighing five ounces each at three second intervals.

In one case there are 300 ounces of hot glass entering the leer per minute and in the other case only 100 ounces of glass. 35 Insulation suitable for the heavy pieces of ware would be too light for the light ware.

The principal object, therefore, of the present invention is to provide means whereby the amount of radiation at any 40 part of the leer may be varied at the will of the operator.

For this purpose the roof of the leer is provided with insulation in the form of layers or leaves which may readily be made 45 effective or ineffective as necessary. The same principle may be applied to other walls of the leer if desired, but in practice it has been found that the proper results are secured by using the leaf insulation on 50 only the roof of the leer.

Further and other advantages will be hereinafter set forth in the accompanying specification and claims, and shown in the drawings, which by way of illustration show what is now considered to be the preferred embodiment of the invention. 55

Fig. 1 is a side elevation of the complete leer.

Fig. 2 is an enlarged sectional elevation through a portion of the leer showing the 60 leaf insulation in various positions of adjustment.

Fig. 3 is a cross section on line 3-3 of Fig. 2.

Fig. 4 is a top plan view of a portion of 65 the roof of the leer showing two leaf sections, one leaf being in elevated position.

As shown in Fig. 1, the leer comprises a long oven-like structure 10 into which the pieces of ware enter one at a time at the 70 right end, to be distributed into rows cross-wise of the leer and then conducted through the leer by conveyor rollers 12 to the discharge opening at the left end of the leer.

The leer has a brick bottom 14 and brick 75 walls 16, (Fig. 3). The roof is also of brick in those sections not provided with the adjustable leaf insulation which is the subject matter of the present invention.

The conveyor rollers 12 which form the 80 floor of the leer are driven by motor 18 through chains 20 and 22.

Above the annealing chamber of the leer is a muffle furnace 24 provided with a stack 26. This muffled furnace is used only when 85 starting the leer or during periods of temporary shut down, etc.

Underneath the leer is an air duct 28 connected to the leer at intervals through openings 30. The openings 30 are regulated by dampers 32, actuated by gears 34 on shafts 36, having a projecting end 38 to which a wrench may be applied. 90

An exhaust fan 40 is connected to duct 28 95 and serves to draw hot gas from the leer at points and in quantities determined by the location and degree of opening of dampers 32.

All of the above construction is described 100

in detail in the above-mentioned Shackelford application.

On top of the side walls 16 is a stationary and very thin metal roof 41. Crosswise of the leer and on top of this roof are spaced thin steel angles 42. The space between each pair of angles 42 is filled with a plurality of leaves 44 which may be of any suitable insulating material, the lower leaf resting 10 on the stationary roof 41 and on one of the angles 42. The angles 42 serve to support one end of the insulating leaves 44 when raised. As shown there are four leaves in each stack, but any appropriate number may 15 be used.

In Fig. 1 and at the right of Fig. 2 all leaves are shown in "down" position so that heat to escape through them must pass through all four leaves. In the second section 20 from the right in Fig. 2 one leaf has been raised out of contact with the other leaves, thereby removing one-fourth of the heat insulation from that roof section and increasing radiation therefrom accordingly. 25 Each succeeding section to the left in Fig. 2 shows one more leaf raised until, in the last section all leaves are raised and the stationary roof 41 of the leer is in direct contact with the outer air.

30 As will be apparent, this construction obviates the need of hinges for the leaves, as well as all necessity for any mechanism, aside from prop. 46, for holding the leaves in raised position. The construction therefore affords an exceedingly simple, cheap, easily operated and effective means for controlling the amount of radiation from any section or zone of the leer.

The above described leaf construction may 40 be applied throughout the length of the leer or only in selected portions of the leer, as is found most suitable for the particular work to be done.

It is to be understood that the invention 45 is not limited to the specific construction herein illustrated and described, but can be embodied in other forms without departure from its spirit, as defined by the appended claims.

50 I claim:

1. A roof for a leer comprising leaves of heat insulating material and means for adjusting said leaves relatively to each other in order to control the amount of heat radiated through said roof.

2. A roof for a leer comprising a plurality of stacks of insulating leaves, said leaves being adjustable relatively to each other for the purpose of controlling the amount of 60 heat radiated from different portions of said leer.

3. A roof for a leer, comprising a plurality of leaves of heat insulating material resting one above the other on said leer, 65 and means for supporting one or more of

said leaves in ineffective insulating position whereby the radiation of heat from said leer may be controlled.

In testimony whereof I hereto affix my signature.

JOHN MAYO.
